APPARATUS FOR ANNEALING MAGNETIC IRON

Herbert A. Field, Hillside, Ill., assignor to Western Electric Company, Incorporated, New York, N. Y., a corporation of New York

Application March 24, 1948, Serial No. 16,788

9 Claims. (Cl. 266—5)

1

This invention relates to an apparatus for heat treating metal parts in a protective atmosphere and more particularly to an apparatus for hydrogen annealing parts within a protective envelope of a neutral atmosphere.

In the processing of iron and other metal parts for use in electromagnetic devices, it is known that, by annealing the parts in an atmosphere of pure hydrogen gas, a substantial increase in certain magnetic properties of the parts may be obtained. However, because of the fact that free hydrogen may readily combine with the oxygen in the air to form an explosive mixture, its use involves an explosive and fire hazard.

An object of the present invention is to provide an apparatus for hydrogen annealing metal parts with a high degree of safety.

In one embodiment of the invention, there is provided a furnace having an inner chamber in which the parts to be annealed are placed and which is enclosed in an outer chamber in which the heating elements are located. Nitrogen gas is fed to the inner chamber to purge the atmosphere of air therein, which outflowing atmosphere is passed through a gas analyzer to indicate the state of purity or density of the nitrogen atmosphere in the inner chamber and, when the air has been completely purged from the chamber and the gas therein is substantially pure nitrogen, the gas analyzer will so indicate and cause visible and audible signals to be operated. Nitrogen is then shut off from the inner chamber and hydrogen is flowed therein to purge the nitrogen gas which passes out from the inner chamber through the gas analyzer. Simultaneously with the shutting off of the nitrogen supply to the inner chamber, nitrogen is fed to the outer chamber for a predetermined period of time to purge the air therefrom and substitute an atmosphere of nitrogen therefor, which forms an envelope of protective inert gas around the inner chamber to prevent infiltration of air into the hydrogen filled inner chamber and to insure a neutral mixture either in the bell or in the hood in case of a leak in the hood. The gas analyzer, when the gas passing therethrough indicates that the gas in the inner chamber is pure hydrogen and has completely purged the nitrogen therefrom, closes a relay circuit to effect a reduction in the rate of feed of hydrogen to the inner chamber. The closing of the relay circuit also effects the closing of a power switch to energize the heating elements of the furnace and to initiate the operation of a program controller unit for controlling

2

the various levels of temperatures and the time at the various levels of temperatures to which the parts are subjected and for controlling the rate of cooling. After the parts have been heat treated and the parts have cooled to the proper point, the flow of hydrogen is cut off and the nitrogen is turned on to flush the inner chamber of all traces of hydrogen, after which the nitrogen is cut off and the furnace is ready to be opened.

The invention will be more fully understood by reference to the following detailed description thereof and the accompanying drawings illustrating somewhat diagrammatically a preferred embodiment thereof in which

Fig. 1 is a vertical central cross sectional view through the furnace;

Figs. 2 and 2a, together, comprise a diagrammatic view of the apparatus; and

Fig. 3 is a wiring diagram of the electrical control portion of the apparatus.

In the embodiment of the apparatus selected to illustrate the invention, a furnace 9 is provided comprising a hollow base 10 enclosing a space 11 therein, a removable hood 12 adapted to fit on the top of the hollow base and form a gas-tight inner chamber 13 in which the parts 15 to be annealed are placed, and a removable bell 16 adapted to fit on the base 10 over the hood 12 to form a gas-tight space 17 around the hood, which space 17, together with the space 11 in the base, forms an outer chamber or envelope entirely enclosing the inner or heat-treating chamber 13.

The piece parts 15 are placed on a perforated platform or grate 19, which is mounted on the upper surface of the base 10 of the furnace and is supported in spaced relation thereto by means of posts 20. The hollow base comprises a top wall 21, a conically shaped wall 25 connected thereto, and a bottom wall 23. A skirt portion 24 formed on the conical wall portion 25 is imbedded in sand 26 contained in a channel 22 formed on the upper outer edge portion of the lower wall 23 and this construction forms a substantially gas-tight seal between the walls 23 and 25. Extending downwardly from the lower portion of the wall 25 is a cylindrical wall or extension 28, from the lower edge of which extends a horizontal flange member 29. The flange member 29 supports an annular rubber gasket 31 and cooperates with the extension 28 and an annular member 30 of L-shaped cross section to form an annular conduit 32, disposed adjacent the gasket 31, through which conduit a coolant

may be circulated to prevent the gasket 34 from becoming overheated.

The hood 12 comprises a cylindrical wall 34, which is closed at the top by the curved wall 35 and has on the lower edge thereof a flared skirt or wall portion 36, from the lower end of which extends a cylindrical portion 38, terminating in an annular bead 39. Extending horizontally from the cylindrical portion 38 is a flange or sealing member 41 having an annular groove for receiving an annular rubber gasket 42 and cooperating with an annular member 43 to form an annular conduit 43, adjacent the gasket 42, through which a coolant may be circulated to prevent damage to the gasket from excessive heat. A plurality of clamping bolts 45, pivotally connected to the flange member 29 and engageable with the member 41, are provided to clamp the hood to the base member.

The bell 16 comprises a cylindrical side wall 50, a top wall 46 and a narrow annular lower wall 47, from the inner edge of which projects an axially extending flange 48, terminating in an annular hollow bead or pipe 49. When the bell 16 rests on the furnace base 10 in its closed position, the annular pipe 49 compresses the rubber gasket 42 to form a gas-tight seal between the lower edge of the hood 12 and the bell 16 and a coolant is circulated through the pipe 49 to prevent deterioration of the gasket due to excessive heat. The bell 16 is lined with a substantial thickness of refractory heat insulating material 51—51 and is provided with a plurality of vertically disposed circumferentially arranged cylindrical heating elements 52. An opening 53 is provided in the upper wall through which a pair of thermocouples 55 and 56 may be inserted into the chamber 17, and gas inlet and outlet pipes 57 and 59 are provided in opposite walls of the bell 16 at the lower and upper levels, respectively, of the bell 16 and the space 17 formed therein.

The base 10 is also provided with a substantial layer of refractory heat insulating material 58 supported on the lower wall 23 and in spaced relation to the upper wall 21 thereof, thus forming the space 11 in the upper portion of the base 10. A plurality of heating elements 60 are mounted in the space 11 and inlet and outlet pipes 61 and 62 pass through the bottom wall 23 and the insulation 58 to permit the circulation of nitrogen gas into and out of the space 11. An opening 64 is provided in the base in which a thermocouple 65 is mounted to extend into the space 11. A pipe 67, extending through the base 12 and terminating at the upper surface thereof, establishes communication with the chamber 13 at a low level therein and a pipe 68, passing through the base 10 and extending upwardly and then laterally across the upper end of the chamber 13 and having openings in the lateral portion, establishes communication with the chamber at an upper level. The base 10 of the furnace is mounted on a suitable support block, such as the block 2.

The pipe 67, communicating with the inner chamber 13 of the furnace (Fig. 2), is connected to one end of a conduit or pipe line 70, which, at its other end, is connected to a port 71 of a manually operated four-way or reversing valve 72. The reversing valve 72 has four ports—71, 73, 74 and 75, and a rotatable core member, which is provided with passages therein for selectively establishing communication between adjacent pairs of ports. A conduit or supply line 76 extends from the port 73 of the reversing valve and has connected therein a pressure regulating valve

77 and a meter 78 and at its other end is connected to or formed into a manifold 79. A pair of branch lines 81 and 82 are connected to the manifold 79 and are connected at a point 83 to, and form a part of, a hydrogen supply line 85, which is, in turn, connected to a suitable source of supply of hydrogen gas. The hydrogen supply line 85, adjacent the juncture of the branch lines, is provided with a manually actuated shutoff valve 87, a normally closed solenoid operated cutoff valve 88, and a pressure switch 89. The branch line 81 has a gas flow regulating valve 90 and a flow scope 91 connected therein and the branch line 82 has a flow control valve 92, a flow scope 93 and a normally closed solenoid operated cutoff valve 94 connected therein.

The pipe 68 to the inner chamber 13 of the furnace is connected to one end of a conduit or pipe line 95, which, at its other end, is connected to the port 74 of the reversing valve 72. An exhaust line 96, connected to the port 75 of the reversing valve 72, has connected therein a back pressure valve 97 and a fire check valve 98 and is connected to a vent pipe 100 extending outside of the building in which the furnace is housed. A line 101, connected to the exhaust line 96 and forming a part thereof, is connected through branched end portions thereof to a pair of gas analyzers 104 and 105, and line 106 from the gas analyzers leads to the vent pipe 100.

The inlet pipe 61 communicating with the space 11 in the base of the furnace and the inlet pipe 57 in the bell 16 of the furnace are connected to the branched ends 108 and 109, respectively, of a nitrogen supply line 110. A portion of the branch line 109 is flexible, to permit the bell 16 to be removed from and replaced on the base of the furnace. The line 110 has connected therein a pressure reducing valve 114, a flow control valve 115, a flow scope 116, a meter 117, a normally closed solenoid operated shutoff valve 118, and a manually operated shutoff valve 119, and is connected at 120 to a main nitrogen supply line 121. Also connected to the main nitrogen supply line 121 at 120 is a branch line 124, which is connected at its other end to the manifold 79 and has connected therein a manually operated shutoff valve 125, a pair of normally open solenoid operated shutoff valves 126 and 127, a flow scope 128, and a flow control valve 129. Connected to the branch line 124 between the valves 126 and 127 is an exhaust line 131, which is connected to the vent pipe 100 and has connected therein a normally closed solenoid operated shutoff valve 132.

The outlet pipe 59 in the bell 16 of the furnace and the outlet pipe 62 in the base 10 are connected to branched ends of an exhaust line 135, which leads to the vent pipe 100 and has a pressure regulating valve 136 and a pressure switch 137 connected therein.

Portions of the apparatus, such as the control valves, the pressure regulating valves, the gas meters, gas analyzers, flow scopes, et cetera, may be grouped together and mounted on a vertical panel or support 138, indicated in dotted lines in Fig. 2 and positioned in a convenient location adjacent the furnace 9.

It will be seen, from the description of the apparatus thus far, that the pipes 67 and 68, leading to different levels in the inner chamber 13 within the hood 16 are connected, respectively, by conduits 70 and 95, to the reversing valve 72 and that the supply conduit 76 and the exhaust conduit 96 are also connected to the reversing valve 72 and, further, that the hydrogen

supply line 85, through its branches 81 and 82, and the nitrogen supply line 121, through its branch 124, are connected to the supply conduit 76 at the manifold 79. Thus, with the shutoff valves 88 and 94 in the hydrogen supply line 85 closed and with the shutoff valves 126, 126 and 127 in the nitrogen supply branch line 124 open, and turning the reversible valve 72 to the position shown in Fig. 2, nitrogen gas is fed through the inlet pipe 67 into the lower end of inner chamber 13 of the furnace to purge the atmosphere within the chamber. The atmosphere within the chamber is displaced by the nitrogen and is exhausted through the pipe 68 and the conduits connected thereto to the outer atmosphere, a portion of the exhaust gases being by-passed through the analyzers 104 and 105 before being vented to the outside atmosphere. By closing the shutoff valves 126, 127 in the nitrogen supply line and opening the shutoff valves 87, 88 and 94 in the hydrogen supply line and rotating the reversing valve 72 one-quarter turn, hydrogen may be fed, through the pipe 68, into the upper end of the inner chamber 13 of the furnace to purge the nitrogen atmosphere from the chamber. The nitrogen atmosphere is flushed from the inner chamber through the pipe 67 and the conduits conducting it to the vent 100 into the outside atmosphere and a portion of the gases being exhausted will pass through the gas analyzers 104 and 105 before being vented to the outside atmosphere. The back pressure valve 97 in the exhaust line 96 and the gas analyzers 104—105 in the line 101 insure a predetermined gas pressure in the inner chamber 13.

The gas analyzer 104 operates to indicate the density of nitrogen (.94) and the gases having a density ranging from 1 to .9 and the gas analyzer 105 operates to indicate the density of hydrogen (.4) and gases having a density ranging from .5 to .2. The gases, as they are exhausted from the chamber 13, are being continuously analyzed and the analyzers 104—105 are continuously indicating the density of the gases in the chamber during the operation of the apparatus.

Nitrogen from the main supply line 121 is supplied through the lines 110, 108 and 109 and the pipes 61 and 57 to the base 10 and the bell 16 of the furnace. The outflowing nitrogen in the base 10 and the bell 16 is conducted through the outlet pipes 62 and 59, respectively, and the exhaust line 135 to the vent 100 and the pressure of the nitrogen atmosphere in the bell 16 and the base 10 is maintained at a predetermined value by the back pressure regulating valve 136 in the line 135. The hydrogen gas, when flowing through the branch lines 81 and 82, is controlled by the control valves 90 and 92, respectively, and the rate of flow thereof is indicated by the flow scopes 91 and 93 and the volume passing through the line 16 is registered on the meter 78. In like manner, the flow of nitrogen through the branch line 124 may be regulated by the control valve 129 and indicated by the flow scope 128 and its volume indicated by the meter 78. The nitrogen passing through the branch line 110 is regulated by the valve 115 to control its rate of flow, which is indicated by the flow scope 116, the volume of the gas being indicated by the meter 117, the pressure of the gas as it enters the furnace being regulated by the pressure regulating valve 114, and the gas pressure in the base 10 and in the bell 16 being regulated by the back pressure valve 136.

The nitrogen supply line 121 (Fig. 2a) is con-

nected to a source of nitrogen supply 145 and, through a branch line 146, to an emergency or standby supply of nitrogen 147. The main and the emergency supplies of nitrogen, as disclosed herein, each comprises compressed nitrogen contained in a battery of cylinders connected to the supply lines in a conventional manner and having suitable pressure regulating valves associated therewith to reduce the high pressure therein to about fifteen pounds in the supply line 121. The pressure of nitrogen gas is further reduced in the line 121 to four ounces by a pressure regulating valve 150, and, before the nitrogen is fed into the furnace, the pressure is still further reduced to 1" water gage by the previously described pressure regulating valve 77. Also connected in the nitrogen line 121 adjacent the pressure regulating valve 150 is a pressure switch 152 and in a portion of the line adjacent the supply 145 are a pressure switch 154 and a normally closed shutoff valve 155. The branch line 146 is provided with a pressure switch 157 and a normally open solenoid operated cutoff valve 158.

The hydrogen supply line 85 is connected to a main supply of hydrogen 160 and, through a line 161, to an auxiliary supply 162. The main and auxiliary sources of hydrogen supply 160 and 162 are shown herein as comprising a battery of tanks containing the compressed hydrogen connected in a conventional manner to the supply line 85. The main and auxiliary supplies of hydrogen and nitrogen may be located in a separate room, where they will be protected from the excessive heat from the furnace or at a distance, with necessary connecting supply lines which may be above ground or carried beneath the surface. The tanks of hydrogen are connected to the line 85 in the usual manner and have the conventional pressure reducing valve means to reduce the high pressure of the gas in the tank to approximately fifteen pounds in the line 85. The pressure of the hydrogen gas in the line 85 is further reduced to four ounces by a pressure regulating valve 165 connected in the line 85 within the building housing the furnace and the hydrogen pressure is further reduced to 1" water gage before passing into the furnace by the aforementioned pressure regulating valve 77.

A pressure switch 167 and a vent line 168 are connected in the line 78 on the low pressure side of the pressure regulating valve 165 and a pressure regulating valve 169 in the line 168 is set to vent the hydrogen from the supply line 85 if the pressure therein is raised a predetermined amount above its normal pressure. Adjacent the supply end, the line 85 is provided with check valve flash arresters 170 and, at points where it enters the building and on the control panel 138, the line 85 is provided with fire check valves 171 and 172, respectively. A filter unit 174, a catalyst unit 175, and a dryer unit 176 are connected in the line 78. The hydrogen gas is filtered as it passes through the filter 174 and whatever oxygen is contained therein is combined with hydrogen in the catalyst unit 175 to form water, which is removed from the gas as it passes through the dryer unit 176 so that, when the hydrogen is supplied to the furnace, it is in a high state of dryness and purity.

The heating elements 52 of the furnace (Fig. 3) are connected to the secondary of a three-phase transformer 177, the primary of which is connected, through electronic contactors 178

and a manually operated switch 179, to a three-phase power line 180. The heating elements 60 in the base 13 of the furnace are connected to the secondary of a transformer 182, the primary of which is connected, through an auxiliary contactor or switch 183, to a pair of conductors leading to the primary of the transformer 177. A pair of wires 184 from the power line 180 are connected, through a manually operated switch 185, to the primary of a transformer 186, the secondary of which supplies 110 volt current through a pair of lines 187 and 188 to various electrical control devices connected thereto.

The gas analyzer 104 has a pointer 190 movable across the scale 191, graduated to read from .9 to 1 to indicate the densities of gases passing therethrough and having densities in this range. With nitrogen flowing into the inner chamber 13, the exhaust gases flowing therefrom into the analyzer 104 cause the pointer 190 to move to the left and, when the pointer reaches the position .94, indicating a gas having a density of approximately pure nitrogen, it actuates a switch 192 to close a secondary circuit of a transformer type relay 194. The primary of the relay 194 is connected by a switch 195 across the power line 187-188 and, when the switch 192 is closed, the relay 194 is actuated to close a pair of contacts 196, which are connected across the power line 187-188 and in series with the pressure switch 167, in the hydrogen supply line 85, the pressure switch 152 in the nitrogen supply line 121, the normally closed contacts 89-1 of the pressure switch 89 in the hydrogen supply line, and a relay 199, which is connected in parallel with a signal lamp 200. Upon the closing of the contacts 196 by the relay 194 of the analyzer 104, the pressure switches 167 and 152 being closed, a circuit is completed to light the lamp 200 and energize the relay 199, which closes a pair of contacts 199-1 connected in series with an alarm bell 204 across the power lines 187-188. Thus, when the pointer 190 of gas analyzer 104 is moved to the point .94 on the scale 191 in response to pure nitrogen gas passing through the analyzer, the signal lamp 200 is lit and the alarm bell 204 is rung to indicate that the nitrogen flowing into the inner chamber has completely purged the air therefrom and that the inner chamber is in condition to receive hydrogen preparatory to the annealing operation.

The operator may now close a push button switch 206 to close a circuit through the coils of the following solenoid actuated valves: the normally closed shutoff valves 88 and 94 in the hydrogen lines 85 and 82, respectively, the normally closed shutoff valve 110 in the nitrogen branch line 110, the normally open shut off valves 126 and 127 in the nitrogen line 124, and the normally closed shutoff valve 132 in the vent line 131. These valves are connected in parallel with each other between the line 188 and one side of the push button switch 206, the push button switch 206 being connected in series with the contacts 196, the pressure switches 152 and 167 to the power line 187. Upon the closing the push button switch 206, the normally open valves 126 and 127 are actuated to cut off the flow of nitrogen gas in the branch line 124, the normally closed valve 132 in the vent line 131 is opened to vent any nitrogen that may pass through the shutoff valve 126, the normally closed valve 110 in the

branch line 110 is opened to permit nitrogen gas to flow through the line 110 and the branched ends 108 and 109 thereof into the base 10 and the bell 16, and the normally closed valves 88 and 94 are opened to permit the flow of hydrogen in the branch lines 81 and 82. With the valve 88 in the line 85 open, hydrogen pressure in the line will actuate the pressure switch 89 and move the two pairs of contacts 89-1 and 89-2 thereof to their opposite positions, thus opening the normally closed contacts 89-1 and closing the normally open contacts 89-2. The contacts 89-2 are connected in parallel with the terminals of the normally open push button switch 206 and, upon being closed, the contacts 89-2 serve to maintain the circuit to the solenoid operated shutoff valves closed after the push button switch 206 has been actuated and while there is hydrogen pressure in the line 85. The contacts 89-1, upon being opened, break the signal circuit to effect the cutting off of the signal light 200 and the alarm bell 204.

To indicate that the reversing valve 72 should be moved to its other operating position when the gas supply to the inner chamber 13 has been changed from one gas to another, audible and visual signal means are provided which are energized or rendered operable in response to the closing of the push button switch 206. A relay 210, connected between the push button switch 206 and the power line 188 is energized when the switch 206 is closed and serves to actuate to their other positions a pair of contacts 210-1 and 210-2 in the signal control circuit. The contacts 210-1, which are normally closed, are connected to a limit switch 214, and the contacts 210-2, which are normally open, are connected to a limit switch 215. The limit switches 214 and 215 are mounted to be actuated in response to the reversing movements of the reversing valve 72. The limit switches 214 and 215 are connected to the power line 187 and are arranged so that the switch 214 is open and the switch 215 is closed when the reversing valve is set to establish communication between the supply conduit 76 and the conduit 78 to pass nitrogen therethrough and when the reversing valve is turned to establish communication between the supply line 76 and the conduit 95 to pass hydrogen therethrough, the switch 214 will be moved to its closed position and the switch 215 to its open position.

The contacts 210-1 and 210-2 are connected to the power line 188 through a relay 217 and a signal lamp 218 arranged in parallel with the relay. The relay 217, when energized, closes a pair of contacts 217-1 arranged in parallel with the contacts 199-1 to complete a circuit to and ring the alarm bell 204. In response to the closing of the push button switch 206 and the energization of the relay 217, the contacts 210-2 will be closed, completing a circuit through the signal lamp 218 and the relay 217, which rings the alarm bell 204. The operator, in response to the lighting of the signal lamp 218 and the ringing of the alarm bell 204, indicating that the reversing valve is in its improper position, may rotate the valve to its other operative position, which movement serves to close the limit switch 214 and open the limit switch 215, thus breaking the circuit to the signal light 18 and the alarm bell 204.

The gas analyzer 105 has a pointer 225 movable along a scale 226, graduated to read from .2 to .5 to indicate the densities of gases passing

through the analyzer and having densities within this range. When the pointer 225, in response to the gases passing through the analyzer, reaches the point .4 on the scale, indicating substantially pure hydrogen, it actuates a switch 227 in the secondary circuit of a transformer type relay 228, the primary of which is connected by the switches 239 to the power lines 187-188, and thus effects the actuation to their opposite position of pairs of contacts 228-1 and 228-2. The normally closed contacts 228-1 are connected in series with the solenoid coil of the normally closed valve 94 in the hydrogen line 82 and between the power line 188 and push button switch 196. The normally open contacts 228-2 are connected in series with the relay 235 between the power line 188 and the push button switch 206. Thus, when the pointer 225 of the gas analyzer has reached the point .4, indicating pure hydrogen is flowing in the inner chamber and has purged the nitrogen therefrom, the contacts 228-1 will be opened to break the circuit to the solenoid of the normally closed valve 94 which is returned to its closed position and shuts off the flow of hydrogen in the branch line 82 and thereby reduces the flow of hydrogen into the inner chamber 13 during the annealing of the parts.

Simultaneously with the opening of the contacts 228-1, the contacts 228-2 are closed to complete the circuit to energize a relay 235 which, upon energization, acts to close a contact 235-1 in an auxiliary contactor control circuit. The contacts 235-1 are connected in series with a solenoid coil 238, a switch 239, and a pair of normally closed contacts 241 across the power lines 187 and 188. The normally open switch 239 is closed by the bell 16 when the bell is lowered to its closed position on the base of the furnace. With the closing of the contacts 235-1, the circuit is completed to energize the solenoid 238 and effect the closing of the contactor switch 183 for supplying current to the heating elements 69.

The normally closed contacts 241 in the auxiliary contactor control circuit are actuated by and form a part of an excess temperature control unit 243, which is connected to the thermocouple 65 in the base 10 of the furnace. The temperature control unit 243 has a second pair of contacts 244, which are normally open. The contacts 241 and 244 are connected in series, respectively, to signal lamps 245 and 246 across the power line 187-188 and are actuated to their opposite positions in response to the rise in temperature in the chamber 13 above the maximum normal annealing temperature therein during the annealing operation. Thus, the excess temperature control unit 243 will act in response to an excess temperature in the base 10 to open the contacts 241 and break the circuit to the solenoid 238, thereby allowing the contactor 183 to return to its open position and disconnect the heating elements 69 from the power line. The lamp 245, which is lighted when the contacts 241 are closed, is deenergized when the contacts 241 are opened and the signal lamp 246 is lighted upon the closing of the contacts 244.

When the normally closed valve 118 in the nitrogen line 110 has been actuated to its open position in response to the closing of the push button switch 206 and nitrogen gas is flowing into the base 10 and bell 16 of the furnace and out through the exhaust line 135, the pressure switch 137 in the exhaust line 135 will be actuated

to close a circuit in the primary of a transformer type relay 250. The secondary of the relay 250 is connected in series with the pressure switches 152 and 187 across the power line 187-188. The relay 250, when actuated, closes a pair of contacts 250-1, which closes a circuit to a coil 253, which, in turn, when energized, closes a pair of contacts 254 to complete a circuit to a timing motor 255. The timing motor 255 acts to close a time delay switch 257 in an electronic contactor control circuit after a predetermined interval of time. The time delay switch 257 is connected across the power line 187-188 and in series with pairs of contacts 258 and 259, a relay 260 and a normally closed pair of contacts 262 of an excess temperature control unit 263. With the contacts 258, 259 and 262 of the electronic contactor control circuit closed, and upon closing of the time delay switch 257, the relay 260 will be energized to actuate the electronic contactors 178 and connect the heating elements 52 and 60 to the power line 180.

The excess temperature control unit 263, which is similar in construction and operation to the temperature control unit 243, is connected to the thermocouple 55 in the bell 16 and acts to open the contacts 262 and thereby effect the deenergization of the relay 260, the opening of the electronic contactors 178 and the disconnection of the heating element 52 from the power lines 180 when the temperature in the bell 16 rises above its normal maximum operating value. The contacts 258 are closed in response to the energization of the relay 238. The contacts 259 of the electronic contactor control circuit are actuated by relay 268 forming a part of a time and temperature control unit, generally indicated at 270. The control unit 270 is connected across the power line 187-188 through switches 271-271 and is connected to a thermocouple 56 in the bell 16 of the furnace. The various controls of the unit 270 are adapted to be set up according to a predetermined program to control, through an operating cycle of the furnace, the temperatures, rate of change of temperature, and duration of the various temperatures in the inner chamber 13 of the furnace.

The pressure switch 157 in the emergency nitrogen supply line 146 is connected in series with an alarm bell 275 across the power line 187-188 and is held open by the gas pressure in the line and operates to close a circuit to ring the bell 275 when the pressure in the line 146 fails. The solenoid coil NO-158 of the normally open solenoid operated valve 153 in the emergency nitrogen supply line 146 is connected in series with a pair of contacts 277 across the power line 187-188. The contacts 277 are closed by the normally closed valve 155 in the main nitrogen supply line 121 when the valve is in its open position. The valve 155 of the "Maxon" type, which is manually movable to its open position and spring-actuated to its normally closed position, is held in its open position by a solenoid operated latch (not shown), the solenoid coil 279 of which is connected across the power line 187-188 in series with one pair of normally closed contacts 154-1 of the pressure switch 154 in the nitrogen line 121. The pressure switch 154 has a second pair of contacts 154-2, normally open, connected in series with a signal bell 283 across the power line 187-188. In response to a reduction in the normal pressure of the nitrogen gas from the main supply 145, the pressure switch 154 will be actuated to close the pair of contacts 154-2, ring-

ing the bell 283, and open the contacts 154-1, breaking the circuit to the solenoid 279, and releasing the valve 155, which is then spring-actuated to its closed position. The closing of the valve 155 shuts off the main supply of nitrogen and opens the contacts 277 to break the circuit to the normally open valve 158 and allow the valve to open and establish communication between the emergency nitrogen supply 147 and the supply line 121.

Operation

When it is desired to anneal a batch of articles 15, the parts are placed in suitable perforated metal baskets or otherwise assembled and stacked on the grate 19 on the base 10 of the furnace and arranged thereon to permit free circulation of gas between the parts.

With the parts properly stacked on the base, the hood 12 may be lowered thereon and clamped to the base and tested to insure a gas-tight juncture therewith, after which the bell 16 may be lowered onto the base and over the hood to establish a gas-tight juncture therewith. Coolants are then circulated through the conduits 32, 43 and 49 to prevent damage to the rubber seals 31 and 42 from the heat of the furnace.

The switches 179 and 185 are now closed to connect the control circuits to the power line 180 and prepare the heating circuits to be connected to the power line and the manually operated valves 87 in the hydrogen line and 119, 125 and 155 in the nitrogen line are opened. Nitrogen gas is now free to flow through the branch line 124 and is fed into the lower end of the inner chamber 13 of the furnace to purge the air therein. The gases purged from the inner chamber 13 pass out through the pipe 68 and the exhaust conduits connected thereto, a portion of the gases passing through the gas analyzer 104, before it is vented to the outside atmosphere. When the air has been purged from the chamber 13, the gas analyzer 104 will indicate that pure nitrogen is flowing therethrough and will effect the operation of the signal bell 204 and the signal lamp 205, indicating that no hydrogen is in the furnace.

The operator may then turn the reversing valve 72 to its other position to connect the gas supply line 78 to the pipe 68 at the upper end of the chamber 13 and the operator may close the push button switch 206 to actuate the various control valves and effect the cutting off of the nitrogen gas to the inner chamber 13, the feeding of hydrogen gas to the inner chamber to purge the nitrogen therein, and the feeding of nitrogen to the base 10 in the bell 16. The hydrogen flowing in at the upper end of the chamber 13 purges the nitrogen therefrom, which is exhausted through the pipe 67 and the exhaust conduits connected thereto, a portion of the gases being exhausted passing through the gas analyzer 105. When the nitrogen is substantially completely purged from the inner chamber, the gas analyzer 105 will indicate substantially pure hydrogen flowing therein and will effect the closing of the valve 94 in the hydrogen branch line 82 to reduce the rate of feed of hydrogen into the inner chamber during the annealing period and also effect the closing of the contactor 183 to connect the heating elements 60 to the main heating circuit. The nitrogen flowing in the outer chamber actuates the pressure switch 137 in the exhaust line 135 and effects, after a predetermined time delay, the actuation of the electronic contactors 178 to con-

nect the main heating elements 52 and the auxiliary elements 60 to the power line 180. The furnace is thus heated and the temperature thereof is controlled through a cycle of operation by the time and temperature control unit 270.

On completion of the annealing of the parts, the operator may close the manually operated valve 87 in the hydrogen line 85, which cuts off the hydrogen gas to the chamber 13 and restores the pressure switch 89 to its normal position to effect the operation of the signal bell 204 and the signal light 200 and also the breaking of the circuits to the solenoid operated control valves, thereby restoring the control valves to their normal operating positions to cut off the flow of hydrogen to the inner chamber and feed nitrogen to the inner chamber of the furnace and also cut off nitrogen to the outer chamber. When the pressure switch 89 is restored to its normal position, it cuts off the current to the relay 210, thus closing the contacts 210-1 and, with the reversing valve 72 in a position to feed gas into the upper end of the inner chamber 13, the switch 214 is closed and the signal lamp 218 is lighted and the signal bell 204 is rung. The operator may then reverse the valve 72, thereby cutting off the signal lamp 218 and the bell 204. When the hydrogen gas has been thoroughly flushed from the chamber 13 and pure nitrogen is flowing therethrough, as indicated by the gas analyzer 104 and the signal elements 200 and 204, the manually operated valve 125 may be closed to shut off the supply of nitrogen to the furnace. After the parts have been sufficiently cooled, the furnace may be opened and the parts removed therefrom.

In the event that the main supply 160 of hydrogen gas should fail during the operation of the furnace, the reduction in pressure would operate to open the pressure switch 167 in the hydrogen line 85 and break the circuits to the various control valves, thus restoring them to their normal positions and shutting off the feed of hydrogen to the inner chamber, shutting off the feed of nitrogen to the outer chamber, and feeding nitrogen into the inner chamber to purge the hydrogen therefrom. With the opening of the pressure switch 167, the relays 210 and 235 are deenergized, which action of the relay 210 closes the contact 210-1 to operate the signal light 218 and the alarm bell 204 and, upon deenergization of the relay 235, the electronic and auxiliary contactors 178 and 183 are opened to disconnect the heating elements from the power line. The operator may then cut in the emergency supply 162 of hydrogen and the pressure thereof will close the pressure switch 167, after which the operator may press the push button 206 to reinitiate the hydrogen feeding portion of the gas feeding cycle of operation. The remaining portion of the cycle will be the same as previously described, with the nitrogen being cut off from the inner chamber, the hydrogen being fed to the inner chamber, and nitrogen being fed to the outer chamber, and after the hydrogen has flushed the nitrogen from the inner chamber and nitrogen is flowed into the outer chamber for a predetermined length of time, the heating elements are reconnected to the power supply to continue the heating of the furnace.

If the main supply 145 of the nitrogen gas should fail, the pressure switch 154 would be actuated to close the contacts 154-2 and operate the signal bell 283 and the contacts 154-1 would be open to and release the valve 155. The valve 155 would return to its normally closed position

and open the contacts 277 and break the circuit to the valve 158 in the emergency supply line 146, thus restoring the valve to its normally open position and connecting the emergency supply 147 to the supply line 121.

In case of failure of power, the solenoid operated control valves mounted on the panel would be restored to their normal operating conditions, cutting off the supply of hydrogen to the inner chamber, cutting off the nitrogen to the outer chamber, and establishing communication between the inner chamber and the nitrogen supply line 121. The "Maxon" valve 155 in the main supply line will close to cut off the main supply of nitrogen gas and the valve 158 in the emergency supply line 146 will be restored to its open position, thus allowing the emergency supply of nitrogen gas to flow into the inner chamber of the furnace and flush the hydrogen therefrom. Thus, even though power failure occurs and the alarm bells and light signals cannot operate to signal the operator, the safety of the apparatus and the operator is assured by the automatic purging of the hydrogen from the inner chamber of the furnace, thus eliminating the fire and explosive hazard inherent in the use of hydrogen gas.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. In a hydrogen annealing apparatus, a furnace having an inner chamber for receiving parts to be annealed and an outer chamber enclosing said inner chamber, outlets from said chambers, conduit means from said chambers to a supply of nitrogen, conduit means from said inner chamber to a supply of hydrogen, electrically operated valve means in said conduit means having a normal position operable to shut off the flow of nitrogen to the outer chamber and the flow of hydrogen to the inner chamber and to establish a flow of nitrogen to the inner chamber to flush the atmosphere therefrom, a gas analyzer connected to the outlet from said inner chamber for indicating the relative densities of the gases purged from said inner chamber and having a control switch operable in response to the flow of substantially pure nitrogen therein, means including a switch operable in cooperation with said control switch to connect said electrically operated valves to a source of power to actuate said valve means to another position to shut off the flow of nitrogen and establish a flow of hydrogen to said inner chamber and to establish a flow of nitrogen to said outer chamber, electrical heating elements in said outer chamber, and means to connect said heating elements to a source of power.

2. In a hydrogen annealing apparatus, a furnace having an inner chamber for receiving parts to be annealed and an outer chamber enclosing said inner chamber, outlets from said chambers, conduit means from said chambers to a supply of nitrogen, conduit means from said inner chamber to a supply of hydrogen, electrically operated valve means in said conduit means having a normal position operable to shut off the nitrogen to the outer chamber and hydrogen to the inner chamber and to feed nitrogen to the inner chamber to flush the atmosphere there-

from, a gas analyzer connected to the outlet from said inner chamber for indicating the relative densities of the gases purged from said inner chamber and having a control switch operable in response to the flow of substantially pure nitrogen therein, means including a manually actuatable switch operable in cooperation with said control switch in said gas analyzer to actuate said valve means to another position to shut off the nitrogen to the inner chamber and feed hydrogen to said inner chamber and nitrogen to said outer chamber, signal means, signal actuating means operable under control of said control switch in said gas analyzer to actuate said signal means to indicate the flow of substantially pure nitrogen in the inner chamber and operable in response to the actuation of said means for actuating said valves to terminate the actuation of said signal, heating elements in said outer chamber, and means to connect said heating elements to a source of power.

3. In a hydrogen annealing apparatus, a furnace having an inner chamber for receiving parts to be annealed and an outer chamber enclosing said inner chamber, outlets from said chambers, conduit means from said inner chamber and said outer chamber to a supply of nitrogen, conduit means from said inner chamber to a supply of hydrogen, electrically operated valve means in said conduit means having a normal position operable to feed nitrogen to the inner chamber and to shut off the hydrogen to the inner chamber and nitrogen to the outer chamber, a gas analyzing means connected to the outlet from said inner chamber for indicating the relative densities of the gases exhausted from said inner chamber and having a first control switch operable in response to the flow of substantially pure nitrogen therein and a second control switch operable in response to the flow of substantially pure hydrogen therein, actuating means including a manually actuatable switch operable in cooperation with said first control switch to connect said electrically operated valve means to a source of power to actuate said valve means to another position to shut off the flow of nitrogen to said inner chamber and to feed hydrogen to the inner chamber and nitrogen to the outer chamber, electrical heating elements in said outer chamber, and means operable in response to the actuation of said second control switch for connecting said heating elements to a source of power.

4. In a heat treating apparatus, a furnace having an inner chamber for receiving parts to be heat treated and an outer chamber enclosing said inner chamber, exhaust outlets from said inner and said outer chambers, conduit means from said inner chamber to a supply of hydrogen and from said inner and said outer chambers to a supply of nitrogen, electrically operated valve means in said conduit means having a normal position operable to shut off the nitrogen to the outer chamber and the hydrogen to the inner chamber and to feed nitrogen to the inner chamber, a gas analyzing means connected to the exhaust outlet of said inner chamber for continuously analyzing the gas exhausted from said inner chamber and having a first control switch operable in response to the flow of substantially pure nitrogen in said analyzing means and having a second control switch operable in response to the flow of substantially pure hydrogen in said analyzing means, valve actuating means including a switch operable in cooperation with said

first control switch to actuate said valve means to another position to shut off the nitrogen and feed hydrogen to the inner chamber and nitrogen to the outer chamber, signal means, signal actuating means operable under control of said first control switch to actuate said signal means to indicate the flow of substantially pure nitrogen in the inner chamber and operable in response to the actuation of said valve actuating means to terminate the actuation of said signal means, heating elements in said outer chamber, and means including a time delay device operable under control of said second control switch to connect the heating elements to a source of power after the lapse of a predetermined interval of time.

5. In a hydrogen annealing apparatus, a furnace having an inner chamber for receiving parts to be annealed and an outer chamber enclosing said inner chamber, outlets from said chambers, conduit means from said outer chamber to a supply of nitrogen, conduit means from said inner chamber to a supply of hydrogen, conduit means from said inner chamber having a branch line connectible to a main supply of nitrogen and another branch line connectible to an emergency supply of nitrogen, electrically operated control valves in said conduit means having a normal position operable to feed nitrogen to the inner chamber and shut off hydrogen to the inner chamber and nitrogen to the outer chamber, gas analyzing means connected to the outlet from said inner chamber for receiving the atmospheres purged therefrom and having a switch control means operable in response to the flow of substantially pure nitrogen therein, actuating means including a manually operated switch operable in cooperation with said switch control means for connecting said electrically operated valve means to a source of power for actuating said valve means to another position to shut off the nitrogen to said inner chamber and feed hydrogen to the inner chamber and nitrogen to the outer chamber, a normally closed auxiliary valve manually actuatable to open position and having electrically operated means for holding said valve in open position connected in said branch line between said electrically operated control valve means and the main supply of nitrogen and electrically connected to a source of power to maintain said auxiliary valve open during the normal operation of the apparatus, and an electrically operated normally open auxiliary valve, connected in the other branch line between said electrically operated control valve means and the emergency nitrogen supply and electrically connected to said source of power for maintaining said normally open auxiliary valve closed during the normal operation of the apparatus, said auxiliary valves being operable in the event of power failure to cut off the main nitrogen supply and cut in the emergency nitrogen supply.

6. In a hydrogen heat treating apparatus, a furnace having an inner chamber for receiving parts to be treated and an outer chamber enclosing the inner chamber, outlets from said chambers, conduit means from the inner chamber to a supply of nitrogen, conduit means from the outer chamber to a supply of nitrogen, conduit means from the inner chamber to a supply of hydrogen, valve means in said conduit means having a normal position operable to feed nitrogen to the inner chamber to flush the atmosphere therefrom and to shut off hydrogen to the inner chamber and nitrogen to the outer chamber, gas

analyzing means connected to the outlet from said inner chamber for receiving the atmospheres exhausted therefrom and having a first switch control means operable in response to the flow of substantially pure nitrogen therein and a second switch control means operable in response to the flow of substantially pure hydrogen therein, pressure responsive means in each of said conduit means to said inner chamber, a first actuating means including a manually actuated switch operable in cooperation with said first switch control means and said pressure responsive means for actuating said valve means to another position to shut off the nitrogen to the inner chamber and feed hydrogen to the inner chamber and nitrogen to the outer chamber, said pressure responsive means being operable to render said first actuating means effective or ineffective in response to variations in gas pressures in said conduit means to said inner chamber above and below, respectively, predetermined values, electrical heating means in said outer chamber, a pressure switch responsive to the gas pressure in said outer chamber, and a second actuating means operable in response to the actuation of said second switch control means in said gas analyzer and in cooperation with said pressure switch for electrically connecting said heating means to a source of power, said pressure switch being operable to render said second actuating means effective or ineffective in response to variation in gas pressure in said outer chamber above or below, respectively, a predetermined value.

7. In a heat treating apparatus, a furnace having an inner chamber for receiving parts to be treated and an outer chamber enclosing said inner chamber, an outlet for said outer chamber, a first conduit means connecting said outer chamber to a supply of nitrogen, a second conduit means connectible to a supply of hydrogen and a supply of nitrogen and having a pair of end portions communicating with the upper and lower ends, respectively, of the inner chamber, electrically operated valve means in said conduit means having a normal first position operable to shut off the nitrogen to the outer chamber and the hydrogen to the inner chamber and to feed nitrogen to the inner chamber to flush the atmosphere therefrom, a reversing valve interconnecting said second conduit means and the pair of end portions thereof, said reversing valve having an outlet port and being operable in a first position to establish communication between said conduit means and one of said pair of end portions and between said outlet port and the other of said pair of end portions whereby nitrogen may be fed into the inner chamber at the lower end and the atmosphere therein exhausted from the upper end thereof, means for actuating said reversing valve to a second position to establish communication between said conduit means and the other of said pair of end portions and between said outlet port and said one of said pair of end portions whereby hydrogen may be fed into the upper end of the chamber and the atmosphere exhausted through the lower end thereof, a gas analyzing means connected to the outlet of said inner chamber for indicating the densities of the gases passing through said inner chamber and having switch control means operable in response to the flow of substantially pure nitrogen therethrough, electrically operated signal means, means operable in response to the actuation of said switch control means for actuating said signal means to indicate the flow of

substantially pure nitrogen in the inner chamber, actuating means including a manually actuatable switch operable in cooperation with said switch control means for connecting said electrically operated valve means to a source of power to actuate said valve means to a second position to shut off the nitrogen to the inner chamber and to feed hydrogen to the inner chamber and nitrogen to the outer chamber, means operable in response to the actuation of said electrically operated valves to said second position to shut off said signal means, and signal means associated with said actuating means and including switch means actuated by said reversing valve for indicating the relative positions of the reversing valve and said electrically operated valve means.

8. In a hydrogen heat treating apparatus, a furnace having an inner chamber for receiving parts to be treated and an outer chamber enclosing said inner chamber, outlets from said chambers, conduit means connecting the inner chamber to a supply of hydrogen, conduit means connecting said inner chamber to a supply of nitrogen, conduit means connecting said outer chamber to a supply of nitrogen, solenoid actuated valve means in said conduit means having a normal position operable to feed nitrogen to said inner chamber and to shut off hydrogen to the inner chamber and nitrogen to the outer chamber, a gas analyzing means connected to the outlet from said inner chamber for indicating the relative densities of the atmospheres exhausted from said inner chamber and having a first control switch means operable in response to the flow of substantially pure hydrogen therein, electrically operated signal means operable under control of said first control switch means to indicate the flow of substantially pure nitrogen in said inner chamber, means including a manually operated switch operable in cooperation with said first control switch means to actuate said solenoid actuated valve means to another position to shut off the nitrogen to the inner chamber and feed hydrogen to the inner chamber and nitrogen to the outer chamber, electrical heating elements in said outer chamber, actuating means for connecting said heating elements to a source of power in response to the actuation of said second control switch means, flow regulating valve means in said conduit means to said hydrogen supply, and actuating means operable in response to actuation of said second control switch means to actuate said flow regulating valve means to another position for reducing the rate of flow of hydrogen to said inner chamber.

9. In a hydrogen heat treating apparatus, a furnace having an inner chamber for receiving parts to be treated and an outer chamber enclosing the inner chamber, outlets for said chambers, conduit means from said inner chamber to a supply of hydrogen, conduit means from said inner chamber and said outer chamber to a supply of nitrogen, electrically operated valve means in said conduit means having a normal position operable to feed nitrogen to the inner chamber and to shut off the hydrogen to the inner chamber and the nitrogen to the outer chamber, gas analyzing means connected to the outlet from said inner chamber for indicating the densities of the gases exhausted from said inner chamber and having a first control means operable in response to the flow of substantially pure nitrogen therein and having a second control means operable in response to the flow of substantially pure hydrogen therein, signal means operable under control of said first control means to signal the flow of substantially pure nitrogen in the inner chamber, means operable in cooperation with said first control means of said gas analyzing means to connect said electrically operated valve means to a source of power to actuate said valve means to another position to effect the shutting off of nitrogen to said inner chamber and the feeding of hydrogen to the inner chamber and nitrogen to the outer chamber, said conduit means to said hydrogen supply having a pair of branches for dividing the flow of hydrogen from said hydrogen supply to said inner chamber, flow valves in said branches for controlling the rate of flow of hydrogen therein, an electrically operated shut off valve in one of said branches, electrical heating means for heating the inner chamber, and actuating means operable under control of said second control means for connecting the heating means and the electrically operated valve in said branch line to a source of power to cause the heating of the inner chamber and the actuation of said valve in said branch to shut off the flow of hydrogen in said branch line.
